AUTOMATIC GUN SELECTOR

George W. Pontius, III, South Bend, Ind., assignor to Bendix Aviation Corporation, South Bend, Ind., a corporation of Delaware

Application February 20, 1940, Serial No. 319,925

8 Claims. (Cl. 89—1)

This invention relates to charging mechanisms for guns. More particularly, it relates to a selector mechanism for charging one or several of a battery of guns having a common charging control. Also it relates to means for indicating the necessity for charging a gun.

The invention is shown as applied to machine guns which are mounted in an airplane, although it is equally applicable to any type of gun charged from a remote source. It is customary in current military practice to increase the fire power of a fighting airplane. One mode of increasing this fire power is to mount guns in batteries at suitable points on an airplane and control the aim and firing from a common or central control point. Another device used to increase fire power is to mount guns in the wings of an airplane and aim them by pointing the airplane at the target. In either case, the person controlling the fire of the guns must do so by remote control. Further, to simplify the tasks of the gunner and save weight, there must be a minimum of controls for such guns.

Charging guns by power means is now common to save the operator the strenuous manual effort required by the high caliber guns in common usage. Charging a machine gun is necessary when a dud shell is inserted in the mechanism or when the machine gun otherwise jams. The operation of charging inserts a fresh shell into the gun and prepares the gun for further automatic firing. The charging means may be hydraulic, such as that described in my joint, copending application, Serial No. 311,978, filed January 2, 1940, on behalf of White and Pontius, or may be pneumatic or electric or some power medium. A single control for a battery of charging mechanisms may be located in the gunner's cockpit.

When an indicating means shows that one gun is not firing it would not be desirable to charge all the guns common to the one control. Rather, it is desirable that the operating guns continue fire and that the jammed guns alone be charged. My invention relates to means to select the gun or guns of a battery of guns which is centrally controlled, and charge the inoperative guns alone without interfering with the operation of the others. Also my invention relates to means which indicate that a gun is in need of charging.

It is therefore an object of my invention to provide means to indicate the necessity of charging a gun.

It is also an object to provide an automatic selector which will allow charging of a jammed gun without charging operating guns. Other ob-

jects and advantages of the invention will be apparent in the following description and claims, which may best be understood when considered in conjunction with the accompanying drawings in which:

Figure 1 is a plan view of an airplane equipped with several batteries of machine guns;

Figure 2 is a sectional view of a dashpot switch used to indicate an inoperative gun and to operate the selector means;

Figure 3 is a sectional view of a hydraulic valve used in conjunction with a hydraulic charger, and showing a pressure switch attached;

Figure 4 is a diagrammatic layout of the electrical and hydraulic controls for the machine gun batteries shown in Figure 1; and

Figure 5 is a side view of a machine gun equipped with the invention in an alternative hookup.

An airplane 10 is shown in Figure 1. This airplane is of the bi-motored type, having a forward pilot's compartment 12 and a central cockpit 14 for the rear gunner. On the rear of cockpit 14 is a dashboard 16, mounting a plurality of hydraulic charging valves 18 and indicating lights 20 directly below these valves. The valves 18 are of the type wherein pressure build-up at the end of a charging stroke causes the valve to shut off the pressure supply and to connect the charging mechanism to exhaust, as fully described in application Ser. No. 311,978 mentioned above. Two gun batteries of machine guns are mounted on the airplane in turrets 22, one at the tail, one at the rear of each motor, and one directly behind cockpit 14. These turrets 22 are aimed and fired by the gunner in cockpit 14 by a control stick 24 retarding a trigger switch 26.

Each gun 28 of a battery has a dashpot switch 30, shown in Figure 2. The switch 30 is mounted at the rear extremity of the breech bolt travel, and is operated by the breech pin 32. A bracket 34 is mounted on gun 28, and retains a cylinder 36. An axially drilled bushing 38 is threaded into the bottom of cylinder 36. A piston rod 40 rides in bushing 38 and has a piston 42 secured to its upper end by a nut. The piston 42 has bleed holes 45 through it. The lower end of piston rod 40 is slotted. A crank 44 is pivoted to bracket 34 at 46 and when one end is struck by breech pin 32, the other end acts through the slot in piston rod 40 to draw piston 42 downward. This crank 44 may be a spring member to absorb the shock of breech pin contact. A spring 48 urges piston 42 upward. The cylinder 36 is closed on top by an insulator

cap 58 threaded into it, which retains a conductor 52 attached to a wire 124.

When trigger switch 26 is closed, besides actuating a trigger mechanism, current charges wire 124. If the gun fires, breech bolt 32 will reciprocate with each shot, kicking crank 44 and pulling piston 42 downward. Between reciprocations, spring 48 pushes piston 42 upward, compressing air in the upper part. The passages 45 meter the air and give a definite period of time for the complete upward stroke of the piston. This period of time is greater than the time between reciprocations of breech pin 32. Should a defective cartridge be inserted into the firing chamber of the gun, or the gun become jammed, piston 42 would go to the top, and piston rod 46 touches contact 52, grounding the electric current of wire 124 through cylinder 36 and bracket 34. The current flow thus established passes through a solenoid in series, opening a hydraulic valve or operating other controls actuating a charging mechanism.

A solenoid valve 58 operated by dashpot 30 is shown in Figure 3. Fluid under pressure controlled by charger valve 18, flows through tube 60 and eventually into the hydraulic charging mechanism 62 which is attached to the side of machine guns 28. The valve consists of a casing 64, having a valve seat 66 mounted therein. A ball 68 held in a steel rod 70 closes off passage through the valve seat 66. The valve rod 70 slides loosely in a casing 72 threaded into casing 64 against an annular packing ring 74. A spring 76 biases valve rod 70 toward valve seat 66. A steel ring 78 fits over casing 72, and a solenoid 80 is placed over it. Solenoid 80 is encased in a steel shell 82, tightened by nut 84 against annular packing ring 86 inserted in casing 64.

When dashpot 30 closes the circuit and energizes solenoid 80 to open valve 58, the passage is open to the charger 62 for high pressure fluid. Should the gunner now open charger valve 18, high pressure fluid would enter charger 62 and retract the breech bolt of gun 28 to reload it. However, it will be seen from examination of Figure 2 that the crank 44 is a short distance along the path of reciprocation of breech pin 32 when electrical contact is made. The breech pin 32 strikes the crank 44 at a point where breech pin 32 is shown by a broken circle. If electrical contact is broken at this instant, solenoid 80 will be deenergized and spring 76 will close the valve 58 stopping further charging action. To eliminate this difficulty, electrical contact must be maintained until the charging stroke is completed. This function is performed by a pressure responsive switch 90, which acts as an additional ground for solenoid 80, responsive to charger pressures. A casing 92 is threaded into casing 64 posterior to valve seat 66. A flexible diaphragm 94 presses a resilient conductor 96 against contact 98 held in an insulator cap 100. Resilient conductor 96 is attached to casing 92, and is thereby effectively grounded.

Fluid under pressure enters casing 92 and presses diaphragm 94 against conductor 96 which bends to make contact with 98. This grounds the solenoid current until the charging stroke is finished, at which time the charging pressure is automatically cut off by control valve 18, and the switch 90 opens. The function of dashpot switch 30 is to open valve 58 until charging pressure is admitted to the charging mechanism by the operator through valve 18.

The hydraulic and electrical circuits for the airplane of Figure 1 are shown in Figure 4. The

hydraulic valves 18 have a pressure connection 110 and an exhaust line 112 with a cylinder line 114 leading to the chargers 62 on the machine guns 28. Hydraulic fluid flows through valve 58 and into the charging mechanism 62. When the charging operation is finished, valve 18 opens to exhaust and the fluid flows back through line 114 through valve 18 to exhaust line 112.

The electrical circuits are of the single line type. A source of potential and current 120 is grounded at one end to the metal frame of the aircraft. The other outlet is connected to a feed wire 122 having the gunner's switch 26 in series with it. Feed wire 122 has four branches 124 leading to the gun turrets, one each for each turret. These lines lead to solenoids 80 which are in series, and the lines are grounded at either dashpot switch 30 or pressure switch 90. When either ground circuit is completed, current flows through lines 124, energizing solenoids 80 and opening valves 58 to charging fluid. An indicator line 130 connects feed line 122 with the switches to ground through an indicating light 20 in series. Whenever dashpot switch 30 closes, current will flow through line 130 lighting indicator 20, as well as through line 124 operating solenoid 80. It is obvious that light 20 could be in parallel with a resistance in line 124 near line 122, eliminating the long wire 130 in Figure 4.

In operation, referring to Figure 1, the gunner is in cockpit 14 facing backward. Upon detecting a target within range, he grasps control stick 24 and points all the turrets 22 at the target. When the sighting mechanism indicates that the target is in the line of fire, the gunner closes switch 26, which fires the guns. If a dud should be inserted in a gun by the automatic loading mechanism, it would not fire, and since recoil reloads a gun, the gun will remain in an inoperative condition.

During firing, the breech pin 32 on the breech bolt, as shown in Figure 2, will strike crank 44, pulling piston 42 downward. But if the gun should cease firing, as when a dud is in the breech, the spring 48 will force piston 42 upward, making contact with 52 and grounding line 124. This causes current to flow through solenoid 80, as shown in Figure 4. The solenoid causes valve rod 70 to lift off of valve seat 66, shown in Figure 3, and passage to gun charger 62 is now open.

The closing of dashpot switch 30 also causes current to flow through light 20, indicating to the gunner that one of the guns of a turret is not firing. The gunner thereupon operates valve 18 controlling the turret of the respective indicator light 20, and fluid under pressure flows through valve 58 into charging mechanism 62. The charging mechanism causes the breech bolt to be moved backward and breech pin 32 to contact the now extended crank 44 of Figure 2. Upon striking crank 44, the contact of line 124 to ground is broken. However, the solenoid 80 is not deenergized because as soon as fluid enters charger 62, the pressure upon diaphragm 94 of Figure 3 closes the contact, and a second switch to ground is closed. In this manner current flows through line 124 until the charging stroke is finished, and the fluid pressure is reduced automatically by valve 18. At the same instant switch 90 opens, indicator light 20 goes out, indicating that all guns are now in firing condition.

By arranging the opening of valve 58 when there is no pressure upon it, a very small and light weight solenoid may be used. It may seem

inconvenient to have the gunner fire a test salvo before he can find out whether or not the guns are in operating condition. But only by actually firing a gun can it be determined that the gun will fire.

An alternative arrangement of dashpot switch 30 with a machine gun adapted for bodily recoil is shown in Figure 5. The machine gun 28 is mounted at the rear in slide support 210 and is supported at the forward end by bracket 212 acting through recoil mechanism 214. The recoil mechanism may be of any known type, allowing the gun 28 to bodily recoil a limited distance to absorb the reaction of projectile acceleration. Dashpot switch 30 is mounted to forward support 212. A member 216 projects from the bottom of machine gun 28, contacting the piston rod 40 of dashpot switch 30 through a transverse bolt 218. It will be noted that in this installation pressure switch 90 is omitted.

In operation, the gunner closes trigger switch 26, firing the guns through a mechanism not shown at the same time line 124 is charged. Upon firing, the gun 28 bodily recoils, sliding in rear support 210, and also sliding in recoil unit 214, which absorbs the shock of projectile acceleration. Catch 216 moves backward with the gun, pulling piston rod 40 with it, breaking the contact to ground of line 124. Upon return of the gun to firing position, the spring 48, shown in Figure 2, pulls piston rod 40 inward to make contact with lead 52. If the gun is firing regularly, catch 216 will again contact piston rod 40 before it can ground line 124. However, if the gun should now jamb, due to a dud being inserted or otherwise, firing ceases, stopping recoil, and piston rod 40 contacts lead 52 grounding wire 124. This causes current to flow through lines 124 and 130, opening solenoid valve 58 and lighting indicator light 20. The gunner then opens charger valve 18, causing fluid to enter charger 62 through conduit 60 and charge gun 28, inserting a fresh shell in the gun. During the charging operation the gun does not recoil, but remains stationary. The trigger mechanism now fires the gun, recoil results and the contact to ground through switch 30 is now broken. Solenoid valve 58 now closes, and indicator light 20 goes out. By using the recoil of the gun, a firing phenomenon, instead of the breech bolt recoil, a charging phenomenon, the necessity of a pressure switch is eliminated. It will be noted that in this embodiment of the invention the switch 30 can be attached to any stationary member or unit.

Although the invention has been described with reference to the electrical control of a hydraulic charger, it is not limited to such specific units. The charging mechanism could be an electrical, magnetic, pneumatic or mechanical servo unit, or other type of unit and still the invention would be applicable. The solenoid 80 would in such case operate suitable switches, valves or controls necessary to operate the charging mechanism. Nor need the control system be electrical. It could be hydraulic, pneumatic or other type. In place of a dashpot switch, a fluid valve could be substituted, and in place of a solenoid, a fluid motor could be substituted. The indicator mechanism could also be different, such as a mechanical signal, fluid operated or otherwise.

Although the invention has been illustrated and described with reference to a particular embodiment thereof, it is not limited to the dis- 75

closure or illustrations or otherwise except by the terms of the following claims.

I claim:

1. In a firing control system for a plurality of automatic guns, a source of hydraulic fluid under pressure, a plurality of hydraulic fluid motors connected to said source and adapted to be associated one with each gun for charging its associated gun in the event of a misfire, a control for said motors for selectively communicating the motors with said pressure source or to atmosphere, an electric circuit adapted to be associated with said guns, a trigger switch in said circuit for firing said guns, solenoid operated valves in said circuit, one of said valves being positioned intermediate the control and each of said hydraulic fluid motors for controlling the flow of fluid to the respective motors, and a plurality of means in said circuit one of said means adapted to be associated with each of said automatic guns and adapted to actuate the solenoid operated valve controlling the flow of fluid to the motors of said one automatic gun upon the misfire of said one automatic gun to permit the flow of fluid to the hydraulic fluid motor of said one automatic gun, said means also suited to prevent actuation of said solenoid operated valve associated with said one automatic gun to arrest the flow of fluid to said hydraulic fluid motor at times when said one automatic gun is firing, and means intermediate each solenoid operated valve and its associated fluid motor and responsive to the pressure in said motor for insuring the actuation of the solenoid operated valve even after the cessation of operation of the first said means.
2. In a firing control system for a plurality of automatic guns, a source of hydraulic fluid under pressure, a plurality of hydraulic fluid motors connected to said source and adapted to be associated one with each gun for charging its associated gun in the event of a misfire, a manual control for said motors for selectively communicating the motors with said pressure source or to atmosphere, an electric circuit adapted to be associated with said guns, a trigger switch in said circuit for firing said guns, solenoid operated valves in said circuit, one of said valves being positioned intermediate the control and each of said hydraulic fluid motors for controlling the flow of fluid to the respective motors, and a plurality of means in said circuit one of said means adapted to be associated with each of said automatic guns and adapted to actuate the solenoid operated valve controlling the flow of fluid to the motor of said one automatic gun upon the misfire of said one automatic gun to permit the flow of fluid to the hydraulic fluid motor of said gun, said means also suited to prevent actuation of said solenoid operated valve associated with said one automatic gun to arrest the flow of fluid to said hydraulic fluid motor at times when said one automatic gun is firing, and means intermediate each solenoid operated valve and its associated fluid motor and responsive to the pressure in said motor for insuring the actuation of the solenoid operated valve even after the cessation of operation of the first said means.
3. In a firing control system for a plurality of automatic guns, a source of hydraulic fluid under pressure, a plurality of hydraulic fluid motors connected to said source and adapted to be associated one with each gun for charging its associated gun in the event of a misfire, a control for said motors for selectively communicating the motors with said pressure source or to at-

mosphere, an electric circuit adapted to be associated with said guns, a trigger switch in said circuit for firing said guns, indicating means in said circuit for indicating the misfire of a gun, solenoid operated valves in said circuit, one of said valves being positioned intermediate the control and each of said hydraulic fluid motors for controlling the flow of fluid to the respective motors, and a plurality of means in said circuit one of said means adapted to be associated with each of said automatic guns and adapted to actuate the solenoid operated valve controlling the flow of fluid to the motor of said one automatic gun upon the misfire of said automatic gun to permit the flow of fluid to the hydraulic fluid motor of said gun, said means also suited to prevent actuation of said solenoid operated valve associated with said one automatic gun to arrest the flow of fluid to said hydraulic fluid motor at times when said one automatic gun is firing, and means intermediate each solenoid operated valve and its associated fluid motor and responsive to the pressure in said motor for insuring the actuation of the solenoid operated valve even after the cessation of operation of the first said means.

4. In a firing control system for a plurality of automatic guns, a source of hydraulic fluid under pressure, a plurality of hydraulic fluid motors connected to said source and adapted to be associated one with each gun for charging its associated gun in the event of a misfire, a manual control for said motors for selectively communicating the motors with said pressure source or to atmosphere, an electric circuit adapted to be associated with said guns, a trigger switch in said circuit for firing said guns, indicating means in said circuit for indicating the misfire of a gun, solenoid operated valves in said circuit, one of said valves being positioned intermediate the control and each of said hydraulic fluid motors for controlling the flow of fluid to the respective motors, and a plurality of means in said circuit one of said means adapted to be associated with each of said automatic guns and adapted to actuate the solenoid operated valve controlling the flow of fluid to the motor of said one automatic gun upon the misfire of said automatic gun to permit the flow of fluid to the hydraulic fluid motor of said gun, said means also suited to prevent actuation of said solenoid operated valve associated with said one automatic gun to arrest the flow of fluid to said hydraulic fluid motor at times when said one automatic gun is firing, and means intermediate each solenoid operated valve and its associated fluid motor and responsive to the pressure in said motor for insuring the actuation of the solenoid operated valve even after the cessation of operation of the first said means.

5. In a firing control system for a plurality of automatic guns, a source of hydraulic fluid under pressure, a plurality of hydraulic fluid motors connected to said source and adapted to be associated one with each gun for charging its associated gun in the event of a misfire, a control for said motors for selectively communicating the motors with said pressure source or to atmosphere, an electric circuit adapted to be associated with said guns, a trigger switch in said circuit for firing said guns, solenoid operated valves in said circuit, one of said valves being positioned intermediate the control and each of said hydraulic fluid motors for controlling the flow of fluid to the respective motors, and a plurality of means in said circuit one of said means adapted to be associated with each gun and each of said means comprising a dashpot and switch and each means operable upon the misfire of the automatic gun with which said means is associated to close said circuit to actuate the solenoid operated valve to permit the unimpeded flow of fluid to the hydraulic fluid motor of said automatic gun, said

adapted to be associated with each gun and each of said means comprising a dashpot and switch and each means operable upon the misfire of the automatic gun with which said means is associated to close said circuit to actuate the solenoid operated valve to permit the unimpeded flow of fluid to the hydraulic fluid motor of said automatic gun, said means also suited to prevent actuation of said solenoid operated valve associated with said automatic gun to arrest the flow of fluid to said hydraulic fluid motor at times when said automatic gun is firing, and means intermediate each solenoid operated valve and its associated fluid motor and responsive to the pressure admitted thereto for continuing the actuation of the solenoid operated valve even after the dashpot means has ceased operation.

6. In a firing control system for a plurality of automatic guns, a source of hydraulic fluid under pressure, a plurality of hydraulic fluid motors connected to said source and adapted to be associated one with each gun for charging its associated gun in the event of a misfire, a manual control for said motors for selectively communicating the motors with said pressure source or to atmosphere, an electric circuit adapted to be associated with said guns, a trigger switch in said circuit for firing said guns, solenoid operated valves in said circuit, one of said valves being positioned intermediate the control and each of said hydraulic fluid motors for controlling the flow of fluid to the respective motors, and a plurality of means in said circuit one of said means adapted to be associated with each gun and each of said means comprising a dashpot and switch and each means operable upon the misfire of the automatic gun with which said means is associated to close said circuit to actuate the solenoid operated valve to permit the unimpeded flow of fluid to the hydraulic fluid motor of said automatic gun, said means also suited to prevent actuation of said solenoid operated valve associated with said automatic gun to arrest the flow of fluid to said hydraulic fluid motor at times when said automatic gun is firing, and means intermediate each solenoid operated valve and its associated fluid motor and responsive to the pressure admitted thereto for continuing the actuation of the solenoid operated valve even after the dashpot means has ceased operation.

7. In a firing control system for a plurality of automatic guns, a source of hydraulic fluid under pressure, a plurality of hydraulic fluid motors connected to said source and adapted to be associated one with each gun for charging its associated gun in the event of a misfire, a control for said motors for selectively communicating the motors with said pressure source or to atmosphere, an electric circuit adapted to be associated with said guns, a trigger switch in said circuit for firing said guns, indicating means in said circuit for indicating the misfire of a gun, solenoid operated valves in said circuit, one of said valves being positioned intermediate the control and each of said hydraulic fluid motors for controlling the flow of fluid to the respective motors, and a plurality of means in said circuit one of said means adapted to be associated with each gun and each of said means comprising a dashpot and switch and each means operable upon the misfire of the automatic gun with which said means is associated to close said circuit to actuate the solenoid operated valve to permit the unimpeded flow of fluid to the hydraulic fluid motor of said automatic gun, said

means also suited to prevent actuation of said solenoid operated valve associated with said automatic gun to arrest the flow of fluid to said hydraulic fluid motor at times when said automatic gun is firing, and means intermediate each solenoid operated valve and its associated fluid motor and responsive to the pressure admitted thereto for continuing the actuation of the solenoid operated valve even after the dashpot means has ceased operation.

8. In a firing control system for a plurality of automatic guns, a source of hydraulic fluid under pressure, a plurality of hydraulic fluid motors connected to said source and adapted to be associated one with each gun for charging its associated gun in the event of a misfire, a manual control for said motors for selectively communicating the motors with said pressure source or to atmosphere, an electric circuit adapted to be associated with said guns, a trigger switch in said circuit for firing said guns, indicating means in said circuit for indicating the misfire of a gun, solenoid operated valves in said circuit, one of

said valves being positioned intermediate the control and each of said hydraulic fluid motors for controlling the flow of fluid to the respective motors, and a plurality of means in said circuit 5 one of said means adapted to be associated with each gun and each of said means comprising a dashpot and switch and each means operable upon the misfire of the automatic gun with which said means is associated to close said circuit 10 to actuate the solenoid operated valve to permit the unimpeded flow of fluid to the hydraulic fluid motor of said automatic gun, said last named means also suited to prevent actuation of said solenoid operated valve associated with said automatic gun to arrest the flow of fluid to said hydraulic fluid motor at times when said automatic gun is firing, and means intermediate each solenoid operated valve and its 15 associated fluid motor and responsive to the pressure admitted thereto for continuing the actuation of the solenoid operated valve even after the dashpot means has ceased operation.

GEORGE W. PONTIUS, III.
